UNITED STATES PATENT OFFICE.

FRANK B. TOWNSEND, OF GENEVA, NEW YORK, ASSIGNOR OF ONE-HALF
TO GEORGE HENRY MARTIN, OF SAME PLACE.

SASH-FASTENER.

SPECIFICATION forming part of Letters Patent No. 561,927, dated June 9, 1896.

Application filed June 29, 1895. Serial No. 554,489. (No model.)

To all whom it may concern:

Be it known that I, FRANK B. TOWNSEND, a citizen of the United States, residing at Geneva, in the county of Ontario and State of New York, have invented a new and useful 5 Sash-Fastener, of which the following is a specification.

This invention relates to an improvement in sash-fasteners, and has for its object to 10 simplify and improve the construction of devices of the character referred to with a view to producing one which may be applied with greater ease and facility to a window-sash, which will operate with greater freedom and 15 reliability, and in which the clamping finger-levers will yield longitudinally to compensate for any bend or deflection in the supporting-rod, in connection with which they coöperate.

A further object of the invention is to provide 20 a simple and efficient lock for engaging the clamping finger-levers and holding the same inoperative when required.

The invention also has other objects and advantages which will appear in the course 25 of the subjoined description.

The invention consists in certain novel features and details of construction and arrangement of parts whereby advantages in point of simplicity and efficiency are attained, as 30 hereinafter fully described, illustrated in the drawings, and finally embodied in the claims.

In the accompanying drawings, Figure 1 is a 35 sectional view through a sufficient portion of a window sash and casing to illustrate the application of the present improvements thereto. Fig. 2 is an inside end elevation of the sash-fastener, showing the locking-plate in engagement with the finger grip-levers. Fig. 3 is a front elevation of the same with 40 the adjacent casing-plate removed. Fig. 4 is a detail perspective view of the inner casing-plate. Fig. 5 is a similar view of the outer casing-plate. Fig. 6 is a detail perspective view of the locking-plate. Fig. 7 is an enlarged detail view of the swinging-rod support 45 and the retaining-plate by which said rod is secured between the beads of the window-casing.

Similar numerals of reference designate corresponding parts in the several figures of the drawings.

Referring to the drawings, 1 designates a pendent supporting-rod, which is disposed between the beads of the window-casing at one side and is provided at its upper extremity 55 with an inwardly-projecting stud, which passes through a perforated retaining-plate 2, secured to the window-casing so as to be flush with the inner surface thereof. This stud is headed upon the inside of the retaining-plate 2, which prevents the rod 1 from escaping and at the same time permits said rod to swing forward upon the removal of the front bead or strip of the casing, for a purpose that will hereinafter appear. 60

The sash-fastener proper comprises a metal casing, which is seated in a mortise cut in the inner adjacent face of that side of the window-sash next to the side of the casing to which the rod 1 is secured, and within said 65 casing is pivotally mounted a pair of finger-levers 3, which are perforated at their outer ends to permit the passage of the supporting-rod 1 and project at their inner ends sufficiently inside of the sash-rail to admit of the 70 same being grasped by the fingers and manipulated for throwing the outer ends thereof out of engagement with said rod. These fingers are pivotally mounted within the rear member 4 of the casing, the latter being 75 formed from a single sheet-metal blank comprising the rear plate proper of the casing and an oppositely-disposed pair of integral flanges 5, projecting forwardly therefrom at right angles. 80

6 designates a forwardly-projecting cross-flange, which is formed by cutting the central portion of the blank and bending the same forward at right angles, said flange extending vertically across between the flanges 5, and 85 being formed with a pair of horizontal slots 7, in which the finger-levers 3 are received and pivotally supported. By means of this construction it will be seen that the finger-levers are adapted to move longitudinally and 90 accommodate themselves to any bends or deflections in the supporting-rod 1, at the same time admitting also of a slight variation in the location of said rod. Inside of the flange 95 6 the finger-levers are formed with alining 100 perforations for the reception of a pin 8, which passes through both and is headed at each

extremity to prevent its escape. A spiral spring 9 is disposed around the pin 8 between the levers 3 and serves by its tension to normally press the inner ends thereof apart and force the outer perforated ends thereof into engagement with the supporting-rod. By means of this construction the finger-levers, even when removed from the casing, are held together and the spring prevented from escaping and becoming lost.

10 designates a locking-plate, which constitutes one of the most important points of the present improvement. This plate is formed from a single piece of sheet metal and provided in the process of manufacture with end trunnions 11, which engage perforations in the flanges 5 of the rear casing-plate, close up to the rear wall thereof. The plate 10 is rocked upon these trunnions by means of an outwardly-projecting finger 12, having a pendant stop 12^a for limiting the inward throw of the plate, and the latter is further provided with a pair of lugs or catches 13, adapted to engage with the finger-levers when rocked forward and spaced apart a distance which will adapt them to hold the inner ends of the levers 3 sufficiently near together to throw the outer ends of said levers out of engagement with the supporting-rod. This locking-plate may be manipulated with perfect ease, is reliable in action, and will be found very useful and convenient when it is desired to remove a window-sash from the casing or where counterbalance-weights are employed.

35 The front casing-plate 14 is perforated in alignment with a corresponding perforation in the inner casing-plate, through which is passed a retaining-screw, which serves to hold the entire fastener in place. This plate 40 is also provided with inwardly-projecting spurs 16, which are adapted to rest between the flanges 5 of the inner plate, and is further provided with a centrally-located integral extension 17, which projects at right angles therefrom across the inner end of the casing and enters an aperture 18 in the inner casing-plate. This extension 17 lies between the finger-levers 3 and serves as a support for said levers in the act of lifting the 50 window-sash, thus adding materially to the strength and durability of the fastening device as a whole.

From the foregoing description it will be apparent that by pressing the finger-levers toward each other they will be disengaged from the supporting-rod 1, thus allowing the sash to be lifted or lowered and retained at desired elevation upon releasing said fingers, the spiral spring interposed between said levers causing the perforated outer ends thereof to grip the supporting-bar in a manner that will be readily understood.

By reason of the particular construction of the casing it will be seen that the same may

be seated entirely within a mortise in the 65 front face of the window-sash, and by reason of said casing being flush therewith it is practicable to apply the securing device to either the upper or lower sash, there being no projection to interfere with the sashes passing 70 each other.

In order to accommodate the supporting-rod 1, the edge of the window-sash is vertically grooved and the perforated ends of the finger-levers are arranged in the plane of said 75 groove in the manner illustrated. By mounting the finger-levers in the casing, as described, the same are capable of longitudinal movement and are adapted thereby to adjust 80 themselves to any crooks or bends in the supporting-rod.

When it is desired to remove a window-sash for any purpose, it will be apparent that after the beading has been taken out in the usual manner the sash may be swung outwardly, this being permitted by the pivotal connection of the supporting-rod 1 with the window-casing. It is now only necessary to manipulate the finger-levers, when the sash 85 may be slid off the rod 1.

90 The device will thus be seen to possess numerous advantages over articles of a similar character heretofore devised.

Having thus described the invention, what is claimed as new, and desired to be secured 95 by Letters Patent, is—

1. An improved sash-fastener comprising a suitable casing, a cross-flange or web disposed within the same and provided with transverse slots or notches, a pair of finger-levers extending through and slidably mounted and fulcrumed in said slots or notches and having their outer ends perforated to engage a supporting-rod, a pin passing through 100 aligning perforations in said levers and headed 105 at its extremities, and a spiral spring surrounding said pin and interposed between said levers, all combined and arranged, substantially as and for the purpose specified.

2. In a sash-fastener, a suitable casing, a 110 pair of levers fulcrumed therein and perforated to engage a supporting-rod, a spring for holding said levers in engagement with the supporting-rod, and a locking-plate pivotally mounted within the casing at or near 115 one end thereof and provided with shoulders or catches for engaging said levers and holding the same out of engagement with the supporting-rod, the same being combined and arranged, substantially as set forth.

120 In testimony that I claim the foregoing as my own I have hereto affixed my signature in the presence of two witnesses.

FRANK B. TOWNSEND.
